CLAIM

The ornamental design for an outdoor storage cabinet as shown and described.

DESCRIPTION

FIG. 1 is perspective view of an outdoor storage cabinet showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the outdoor storage cabinet in an opened state; and

FIG. 9 is another perspective view of the outdoor storage cabinet in the opened state; and,

FIG. 10 is an enlarged view of the encircled portion in FIG. 9.

The small evenly spaced dashed broken lines depict portions of the article that form no part of the claimed design. The dot-dash broken lines encircling portions of the outdoor storage cabinet in FIG. 9 and illustrated in enlarged views in FIG. 10 form no part of the claimed design.

1 Claim, 9 Drawing Sheets
